UNITED STATES PATENT OFFICE.

JOHN CLIFFORD WHITRIDGE, GEORGE TEWKSBURY JOHNSON, AND HARRY HAMILTON WOLFE, OF COLUMBUS, OHIO, ASSIGNORS TO THE BUCKEYE STEEL CASTINGS COMPANY, OF COLUMBUS, OHIO.

CAR-COUPLING DEVICE.

Application filed November 5, 1923. Serial No. 672,855.

To all whom it may concern:

Be it known that we, JOHN C. WHITRIDGE, GEORGE T. JOHNSON, and HARRY H. WOLFE, citizens of the United States, and residents 5 of Columbus, in the county of Franklin and State of Ohio, have invented certain new and useful Improvements in Car-Coupling Devices; and we do hereby declare the following to be a full, clear, and exact 10 description of the invention, such as will enable others skilled in the art to which it appertains to make and use the same.

This invention relates to improvements in car coupling devices, the subject-matter of 15 this application having been originally shown, described and claimed in an application for patent filed by J. C. Whitridge, G. T. Johnson, H. W. Stertzbach and H. H. Wolfe, March 22, 1923 and designated by 20 Serial No. 626,934.

The present improvements are intended more particularly for use on roads which are in the transition period of substituting the M. C. B. automatic coupler for the knuckle 25 and screw type of coupler. On such roads, some cars are equipped with the automatic coupling while others retain couplers of the hook type and it is frequently necessary to connect the different types of couplers. While devices for effecting this result have been heretofore produced, considerable difficulty has been experienced in 30 avoiding jamming of the connecting devices when the cars come together in buffering position, and it is the primary object of the invention to provide inexpensive and efficient means for connecting a hook or European type of coupler with the automatic coupler which will provide ample clearance for 35 the transition links when the cars are in buffering position.

A further object of the invention is to provide a connection which will be flexible so as to accommodate itself to differences in 45 the height of the two couplers but maintain the coupled relation until separation of the cars is desired.

With these and other objects in view, the invention consists in certain novel features 50 of construction and combinations of parts as hereinafter set forth and pointed out in the claims.

In the accompanying drawings; Figure 1 is a plan view of coupling devices embody-

ing our invention; Figure 2 is a side elevation of the structure shown in Figure 1, the parts being shown in the position assumed when the cars come together; Figure 3 is a plan view of another form of the invention, and Figure 4 is a side elevation 60 of the structure shown in Figure 3.

In the drawings, 1 designates an M. C. B. type of automatic coupler and 2 designates the hook of a coupler of the European type. In carrying out the invention, the 65 knuckle 3 is cored out so as to form an opening vertically therethrough adjacent its free end to receive a pin 4, and also form a horizontal notch or slot 5 in said end of the knuckle midway the height thereof and intersecting the vertical opening, the forward end of said notch or slot being flared, as shown at 6. An eye 7 is employed which is fitted within the notch or slot 5 and through which the pin 4 is engaged so that 70 the eye will be firmly held to the knuckle and will transmit pulling strain thereto. The eye 7 is formed integral with an eye 8 which is disposed vertically in front of the knuckle and rests in the flared end 6 of the 75 notch 5, as shown in Fig. 2, the two eyes 7 and 8 forming a twisted link and constituting, with the pin 4, a pin and link coupling. On the rear side of the eye 7 is a lug 9 the 80 ends of which project above and below the eye and thereby bridge the notch or slot 5 and bear against the rear side of the knuckle to aid in transmitting pulling strain to the knuckle and thence to the coupler draw-head, it being understood that the knuckle 90 is locked in coupled position in the usual manner. The lug 9 may be omitted, if desired, and the device would still give satisfactory service, but if the lug be used a 95 lighter pin may be employed and the vertical opening through the draw-head may be correspondingly reduced. Engaged with the eye 8 is one end of a straight link 10 which may turn on a vertical plane pivotally in the eye, and the opposite end of the link is pivotally engaged through the eye 11 at the end of a link 12 which is engaged over the bill of the coupler hook. It 100 is to be noted that the link 12 has a somewhat trapezoidal form, its sides converging toward the eye 11 which latter extends centrally from the top and bottom of the link at the end thereof farthest removed from

the coupler hook. The opening of the link 12 is thus given an outline corresponding to the cross-sectional contour of the coupler hook so that while it may be easily coupled therewith, it cannot twist thereon although it may swing in the plane of the hook. The connection consisting of the link 10 and the members engaged therewith will thus be held in the line of draft although pivotal movement about the pin 4 may occur to accommodate the position of the cars when passing around curves and pivotal movement at the distal ends of the links 10 and 12 permit the connection to assume an inclination necessary to accommodate differences in the heights of the cars and also to absorb the vibration of the same when in motion.

Normally, under load, the cars will be apart and the coupling connection will be straight and taut. Various conditions, however, cause the cars to approach and buffers are provided on the car ends to limit the approaching movement, but, with most of the devices heretofore produced, the movement of the cars toward each other results in jamming and breakage of some of the parts. With the device of this invention, jamming and breaking is avoided inasmuch as a joint is provided between the connections with the respective couplers so that when the cars come together the links 10 and 12 fold or hinge downwardly between the two couplers, as shown in Fig. 2 without jamming against either coupler.

In Figures 3 and 4 is shown a form of the invention in which the horizontal notch or slot in the knuckle is omitted and the pin 13 is provided with an eye 14 at its upper end, a link 15 being engaged with said eye and flexibly connected with the coupler hook. In this form of the invention, the folding of the connection occurs above the horizontal line of draft instead of below it as in the previously described form.

Having fully described our invention what we claim as new and desire to secure by Letters-Patent, is:—

1. In a device of the class described, the combination of an automatic coupler including a knuckle, and a vertical pin in the

free end portion of the knuckle, the free end of the knuckle having a horizontal notch therein, an element fitting within said notch and about said pin, a hook coupler, and connections between said element and the hook coupler permitting relative pivotal movement of the same, said connection having a part disposed behind the notch in the knuckle. 55

2. In a device of the class described, the combination of an automatic coupler including a knuckle and a vertical pin in the free end portion of the same, a link fitted pivotally about the pin within the knuckle, a hook coupler, a link engaged closely about the bill of said hook coupler and conforming to the cross-sectional outline of the same and having a central vertically-disposed eye at its outer end, and a link connection between said eye and the first-mentioned link. 60

3. In a device of the class described, the combination of an automatic coupler including a knuckle having a horizontal notch in its free end, the front end of said notch being flared, and a pin mounted in the knuckle and passing across said notch, a twisted link having one end engaged in said notch and about the pin and its opposite end conforming to the contour of the flared front end of the notch, a hook coupler, and a link connection between said twisted link and the hook coupler. 75

4. In a device of the class described, the combination of an automatic coupler including a knuckle having a notch in its free end, and a pin mounted in the knuckle and passing across said notch, an eye engaged in said notch and about the pin, a lug on said eye bridging the notch at the rear side of the knuckle, a hook coupler, and a link connection between said eye and the hook coupler. 85

In testimony whereof, we have signed this specification in the presence of two subscribing witnesses.

JOHN CLIFFORD WHITRIDGE,
GEORGE TEWKSBURY JOHNSON,
HARRY HAMILTON WOLFE.
